United States Patent Office.

JOB SMYTHE, OF WILLING, AND CHAUNCEY DEXTER, OF INDEPENDENCE,
NEW YORK.

Letters Patent No. 99,489, dated February 1, 1870.

IMPROVED STOVE-PIPE SHELF.

The Schedule referred to in these Letters Patent and making part of the same

To all whom it may concern:

Be it known that we, JOB SMYTHE and CHAUNCEY DEXTER, the former of Willing, and the latter of Independence, both in the county of Allegany, and State of New York, have invented a new and useful Improvement in Stove-Pipe Brackets or Shelves; and we do hereby declare the following to be a clear and exact description of the nature thereof, sufficient to enable others skilled in the art to which our invention appertains, to fully understand and use the same, reference being had to the accompanying drawings, making part of this specification, in which—

Figure 1 is a top or plan view, and

Figure 2 is a central longitudinal section in line α , fig. 1.

Our invention is an improvement in the class of brackets or shelves which is applied to stove-pipes; and consists in the construction and combination of certain parts, as will be hereinafter more fully described.

In the drawings—

A may represent a section or piece of stove-pipe, of ordinary form and construction.

B is a shelf or tray, which consists of a bottom, B', and a rim, C, the two together forming a pan-shaped vessel, which may or may not have a cover, as most desirable.

D represents a flat piece or strip of metal, which is hinged or pivoted to the shelf B at the point G, and adapted to swing horizontally therefrom.

The shelf B is cut out at one side, in circular form, so as to fit around the pipe A, and the strip D is bent, to encircle it, and, by means of the joint C, the tray is readily secured to and detached from the pipe.

In order to hold the bracket in place, it is necessary that the hinged piece D be firmly connected to the shelf B. I provide for this, by means of lugs or ears, eyes or rings, which are respectively formed on the piece

D and shelf B, and through them there is passed a pin, F, which should be so made as to be easily removed.

E is a set-screw, which passes into the band D, and is intended to bear against the stove-pipe.

A series of hooks, H, is connected to the shaft, and serve the purposes of holding the lifters for the stove-covers, towels, &c.

It is merely necessary to apply the tray to the stove-pipe, connect the shelf and band by the pin F, and tighten the set-screw, when it will be seen that the tray is firmly held in place. A simple and convenient device is produced, which will retain and keep warm articles of food, &c., by utilizing the heat from the pipes. When the tray is not needed, it may be quickly removed and stored away.

In removing it, the set-screw E is loosened, and the pin F withdrawn, when the subsequent operation is readily apparent. The set-screw E not only serves to hold the shelf in place, but permits the adjustment thereof to the desired height. Either side of the tray may be used uppermost, although it is preferable to have it as shown in fig. 2.

We are aware that it is not new to construct shelves or brackets which are applicable to stove-pipes; but we are not aware that they possess the simplicity and readiness of application and detachment, as presented in our device; we therefore do not claim the aforesaid broadly; but having described our invention,

We do claim, the tray B, hooks H, hinged strip D, and set-screw E, combined and arranged together, as set forth and shown.

JOB SMYTHE.
CHAUNCEY DEXTER.
